W. O. COLBURN

TIRE CHAIN TIGHTENER AND LOCK

Filed June 8, 1925.

Patented Mar. 2, 1926.

1,575,545

UNITED STATES PATENT OFFICE.

WALTER O. COLBURN, OF BANGOR, MAINE.

TIRE-CHAIN TIGHTENER AND LOCK.

Application filed June 8, 1925. Serial No. 35,783.

To all whom it may concern:

Be it known that I, WALTER O. COLBURN, a citizen of the United States, residing at Bangor, in the county of Penobscot and 5 State of Maine, have invented certain new and useful Improvements in Tire-Chain Tighteners and Locks; and I do declare the following to be a full, clear, and exact 10 description of the invention, such as will enable others skilled in the art to which it appertains to make and use the same.

My invention relates to improvements in devices for connecting the ends of chains, and the primary intent, is to utilize the 15 device for connecting the usual side chains of anti-skid chain structures, commonly used on motor vehicles.

It is the object of the invention to provide a simple and inexpensive construction, 20 yet one which will be very efficient, easy to operate, and embodies unique means for locking a chain tightening lever in operative position.

With the foregoing in view, the invention 25 resides in the novel subject matter hereinafter described and claimed, the description being supplemented by the accompanying drawing.

Figures 1, 2 and 3 are side elevations 30 showing different positions of parts from the time the fastener is initially engaged with the free end of the chain, to the time when said fastener reaches its locked position.

Figure 4 is an edge view.

Figures 5, 6 and 7 are perspective views 35 of the three main parts of the device, hereinafter described.

The numeral 1 on the drawing designates 40 an elongated metal plate having a link-receiving notch 2 in one edge, said notch being disposed near one end of said plate. The opposite end of this plate may well be widened as indicated at 3, although this 45 is not absolutely essential. Fulcrumed at one of its ends, to the first named end of the plate 1, is a link-engaging chain-tightening lever 4, the fulcrum being indicated at 5, the inner end of said lever being preferably formed in one edge with a link-receiving notch 6 for registration with the 50 notch 2, when the lever is swung to a position at one side of the plate 1, as shown for instance in Figs. 2 and 3. The outer end of the lever 4 may well be provided with a lateral finger 7 projecting from the

edge of said lever remote from the notch 6, said finger serving to facilitate insertion of the lever through one of the links 8 of the chain.

Pivoted between its ends at 9, to the widened end 3 of the plate 1, is a lever-locking member 10 which preferably comprises a relatively long side plate 11 and a comparatively short side plate 12, the two plates 65 being suitably joined to each other at the outer end of the member 10. The two plates straddle the plate 1 and the pivot 9 passes through them, and the joined outer ends of these plates are connected with one 70 of the end links 13 of the chain. The inner end of the relatively long plate 11, is provided with an L-shaped finger 14, one portion of which is adapted to abut the outer edge of the lever 4, when the latter is in 75 operative position, while the remaining portion of said fingers then lies against the outer side of said lever to hold the latter against sidewise movement away from the plate 1.

In applying the device, the lever 4 is inserted through the link 8, and while the locking member 10 is held substantially in the position of Fig. 1, said lever is swung inwardly to the position of Fig. 2, in which 80 position it is limited by a suitable stop 15 on the plate 1. The locking member 10 is now swung to the position longitudinally of the fastener as shown in Fig. 3 and Fig. 4, and it then serves to effectively hold 90 the lever 4 in operative position, so that there is no danger of the fastener being accidentally released during operation of the chain.

The invention is very simple and inexpensive, yet it will be obvious that it is efficient and desirable. On account of these existing advantages for the details disclosed, such details are preferably followed. However, within the scope of the invention as 100 claimed, modifications may be made.

I claim:

1. A chain tightener and lock comprising an elongated plate, a link-engaging chain-tightening lever fulcrumed to one end of 105 said plate, said lever being adapted for inward movement to a position longitudinally of the plate, means for limiting the inward swinging of said lever, and a lever-locking member pivoted between its ends to the end 110 of the plate remote from the lever fulcrum, the outer end of said lever-locking mem-

ber being adapted for connection with one end of the tire chain while the inner end of said lever-locking member is adapted to abut said lever and hold it against outward swinging.

2. A chain tightener and lock comprising an elongated plate having a link-receiving notch in one edge near one end, a link-engaging chain-tightening lever fulcrumed at 10 one end to said end of the plate and having a link-receiving notch in one edge to register with the first named notch when the lever is inwardly swung to a position at one side of the plate, the other edge of said 15 lever being provided at the free end of the latter with a projecting finger, means for limiting the inward swinging of the lever, and a lever-locking plate pivoted between its ends to the end of the first named plate 20 remote from the lever fulcrum, the outer end of said lever-locking plate being adapted for connection with one end of a chain, the inner end of said lever-locking plate being provided with an L-shaped finger to engage 25 the lever and hold it both against outward

swinging and against sidewise movement from the first named plate.

3. A chain tightener and locking device comprising an elongated plate, a link-engaging chain-tightening lever fulcrumed at 30 one end of said plate, said plate having a link-receiving notch in one edge near the fulcrum point of said lever, said lever being adapted for inward movement to a position longitudinally of the plate and having a 35 link-receiving notch registrable with the notch in said plate, a projecting finger at the free end of said lever, a stop finger on the plate to limit the inward swing of said lever, and a lever-locking plate fulcrumed 40 between its ends to the end of said plate remote from the lever fulcrum and adapted for connection to one end of a chain, and means on the lever locking plate for holding the lever in engagement with said stop finger.

In testimony whereof I have hereunto affixed my signature.

WALTER O. COLBURN
